UNITED STATES PATENT OFFICE

GEORGE BOOTH, OF TORONTO, ONTARIO, CANADA, ASSIGNOR TO BOOTH & SON, OF SAME PLACE.

BATH.

SPECIFICATION forming part of Letters Patent No. 324,293, dated August 11, 1885.

Application filed September 22, 1884. (No model.) Patented in Canada September 30, 1884, No. 20,305.

To all whom it may concern:

Be it known that I, GEORGE BOOTH, of the city of Toronto, in the county of York, in the Province of Ontario, coppersmith, have invented certain new and useful Improvements in Baths; and I do hereby declare that the following is a full, clear, and exact description of the same.

The object of the invention is to devise a simple and effective arrangement of pipes and valves by which hot and cold water may be either admitted into the bath at its bottom or into a pipe arranged to elevate the water to a shower-rose or wash hand-basin, and also to devise a wash hand-basin to overhang the bath, and preferably arranged to receive its water and drain into the same pipes by which and into which the bath is supplied and drained; and it consists, first, in placing a four-way valve in the junction-pipe between the hot and cold water supply pipes, and connecting the said four-way valve with a pipe arranged to discharge into the bottom of the bath, and also with a pipe arranged to elevate the water, as specified, the said four-way valve being so arranged that communication with the elevating-pipe is cut off during the period when the passage-way into the bath is opened; and, secondly, in placing a hand-basin over the bath, preferably by pivoting the drain-pipe of the basin on an elbow connected to and leading into the overflow-pipe of the bath, the said basin drain-pipe being arranged to carry the basin, the whole being connected, arranged, and provided with all necessary detail parts, substantially as and for the purpose hereinafter more particularly explained.

Figure 1 is a perspective view, showing the end of a bath provided with my improvements. Fig. 2 is an enlarged sectional detail of the four-way valve and the pipes leading from it into the bath and basin. Fig. 3 is an enlarged detail, partially in section, showing the four-way valve and its connection with the junction-pipe leading into the hot and cold water cocks.

In the drawings, the letter A represents a junction-pipe or passage-way. It is formed, as shown in Fig. 3, with two extensions, *a a*,

provided with openings through which the water from the hot and cold water supply enters in the usual way. *b b* are extensions provided with openings directly opposite the openings in the extensions *a a*. Each extension *b* is provided with a cap, through which extends a threaded stem for operating the valve B, which valve, stem, and cap are of the ordinary construction commonly used. This pipe A is also provided with two central orifices, *c d*, the latter externally-threaded to receive the pipe D, which discharges into the bath, while the former is threaded internally to receive the casting *d'*, which is provided with a cross-bar, *e*, having openings for the passage of water, as shown in Fig. 2, and a central opening to receive the stem of the valve C, as shown in Fig. 3. At its upper end this casting is externally-threaded to receive the coupling E', which may or may not be made integral with the pipe E, which discharges into the basin F. The valve C, which is two-faced, is placed in the center of the pipe A, with its stem projecting through the pipe E, as shown, and is provided with two seats, one formed above the pipe D, and the other formed on the bottom of the casting *d'*, as shown in Fig. 3. The pipe E discharges into the basin F, or may be arranged to discharge into a shower-rose of the ordinary description.

G is an overflow-pipe extending from the usual point to the main drain-pipe H, which is shaped substantially as shown, and connects with the interior of the bath through the plug-hole I.

A trap, N, is placed, as indicated, in the pipe H, which is fixed, with the other pipes, permanently to the bath, so that an ordinary tinsmith can make all the connections after the bath has been placed in position.

J is a plug of the ordinary kind, which fits into a seat formed in the plug-hole I, the surface of the bottom of the bath, so as to leave room between the bottom of the bath and the top of the plug for a passage-way to connect the pipe D with the interior of the bath. It will thus be seen that while there is only one opening in the bottom of the bath

the inlet-pipe through which the supply of fresh water is furnished to the bath is entirely distinct from the outlet-pipe through which the waste water escapes.

- 5 When the wash-basin F is to be used in connection with the bath, I usually form the waste-pipe K, leading from the basin F, substantially in the shape shown, and of sufficiently-strong material to support the weight 10 of the basin. The bottom end of this waste-pipe K, I fit into the elbow-shaped socket L, which leads into the overflow-pipe G, and is perforated, as indicated, to allow the water in the bath to escape. A bracket, M, which is 15 screwed to the top of the bath, forms a support or stay for the pipe, K, so that the said pipe may with safety be made to swivel in the elbow-socket L, for the purpose of adjusting the position of the basin.
- 20 Although it will be preferable to connect the basin to the bath in the manner described, it will of course be seen that a portion of the object of my invention would be secured by simply suspending an ordinary basin over 25 the bath, so that the basin can be used independent of the bath, while the bath not only serves as a bath, but also acts as a receiver for catching any overflow water or splashing of the basin.
- 30 The four-way cock herein described may be used in connection with a wash-basin provided with a shower-rose, in which case the pipe D would discharge into the basin and the pipe E into the shower-rose.
- 35 What I claim as my invention is—

1. The drain-pipe H, overflow-pipe G, con-

necting with the interior of the bath through the plug-hole I, and the pipe D, arranged to discharge into the bath through the said plug-hole I, in combination with a plug, J, seated 40 in the plug-hole I below the point where the pipe D connects with the said hole.

2. In combination with a tub, its overflow-pipe, and a basin supported over said tub, the waste-pipe K, connected to the basin F, and 45 elbow-socket L, arranged to support the pipe K, and connect the same with the tub-overflow-pipe, substantially as and for the purposes specified.

3. In combination with bath-tub having 50 a basin suspended thereover, a swiveled drain-pipe, as K, supporting said basin and connecting the same with the drain-pipe of the tub, substantially as and for the purposes described.

4. The pipe A, provided with extensions a a and b b, said extensions b b being provided with a valve, B, as described, said pipe A having also orifices c d, the latter communicating with the pipe D, and the former internally 60 threaded, in combination with the casting d', provided with openings for the passage of water and the stem of the valve C, the pipe E, connected with said casting, and the two-faced valve C, provided with two seats, one above 65 the pipe D and the other formed on said casting, substantially as described.

Toronto, August 22, 1884.

GEORGE BOOTH. [L. S.]

In presence of—

CHARLES C. BALDWIN,
JAMES LOMAS.
